(57) **CLAIM**

The ornamental design for a hair mask jar, as shown and described.

DESCRIPTION

FIG. 1 is a perspective view of a hair mask jar showing my new design.

FIG. 2 is another perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

The broken lines in the drawings depict portions of a hair mask jar that form no part of the claimed design. The "Karseell" text logo forming part of the claimed design is a registered trademark of the Applicant, Guangzhou Chinchy Cosmetic Co., Ltd.
